CLAIM

The ornamental design for an intelligent toilet seat cover, as shown and described.

DESCRIPTION

FIG. 1 is a front view of an embodiment of an ornamental design for an intelligent toilet seat cover showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof; and,

FIG. 8 is another perspective view showing the intelligent toilet seat cover in a use state.

The broken lines depict portions of the intelligent toilet seat cover in which the design is embodied that form no part of the claimed design.

The shade lines in the figures show contour and not surface ornamentation.
